UNITED STATES PATENT OFFICE.

WILLIAM G. VENARD, OF LONG BEACH, CALIFORNIA.

CONCRETE-FORM APPARATUS.

Application filed April 2, 1928. Serial No. 266,803.

This invention relates to concrete form apparatus.

In erection of concrete walls and columns it is the practice to use wooden or metal mold panels and to stay these from the outside by means of uprights and cross-bars, generally of wood. This necessitates a considerable quantity of stock and the use of much time and skillful labor. A very material amount of waste is entailed by demolition of the wooded false work.

An object of my present invention is to overcome the above disadvantages and provide a metal form upright and cross-tie capable of being readily erected and of being collapsed or extended telescopically to different lengths as may be necessary.

Numerous additional objects, advantages and features of construction, combination and details of means will be made manifest in the following description of the herewith illustrative apparatus; it being understood that modifications, variations and adaptations may be resorted to within the spirit, scope and principle of the invention as it is more directly claimed hereinafter.

Figure 1 is a top end view of a form stay or upright.

Figure 2 is an inner face elevation of the upright, (medially broken).

Figure 3 is a side elevation thereof.

Figure 4 is a perspective of telescoped parts of the upright.

Figure 5 is a detail perspective of a filler strip of the stay device.

Figure 6 is a plan and horizontal section of a part of an erected form apparatus.

Figure 7 is a vertical section of the form.

Figure 8 is a sectional detail showing a tie-wire disposed between the spaced filler strips.

Figure 9 is a horizontal section of a concrete column; showing its panels braced by short telescopic stays.

Figure 10 is a sectional elevation of a stirrup for linking ends of the stays of a column form; as in Fig. 9. Figure 11 shows a pin.

The present concrete form support includes an inner unit composed of a pair of spaced channels 2-3 having their flanges 4-5 and 6-7 turned outward as best shown in Fig. 4. The channels are rigidly and permanently cross-connected by spacers 8 at suitable pitch to provide a space for the reception of form tie wires 10, Figs. 6 and 7.

These inner units may be of any length

and cross-dimensions, and are slidable in outer units which, each, include L-members 11-12 whose flanges 13-14 are rebated at the inner corners to receive the flanges 5-7 of the inner unit. The flanges 5-7, 13-14 all have inner faces in a common plane to lie flush against interposed mold panels P, as shown in Fig. 6; to which these flanges may be nailed or cleated in any desired manner; the cross-wires 10 serving to hold the erected stays and panels against spreading action of the load in the mold.

The outer L-members 11-12 lie between the respective flanges 4-5 and 6-7 and are held in such position by outer U-clips 15 fitting slidably over the flanges 4 and 6. The U-clips are pitched at suitable distance and along them are reach or filler pieces 16-17 of angle iron having one flange notched at 18, Fig. 5, to straddle down over interposed clips 15. These fillers are spaced and register with the inner channels 2-3 to form a rest for tie-rings 19 which are in loops 10^a of the tie-wires 10, whose inner ends are clinched over the mold panels P.

When the stay units are set vertically as standards, to support panels, they are telescoped in or out to the desired length and the tie-wire 10 is rove across from standard. In some places the tie-rings 19 will bear against the flanges 4-6 of the inner unit I and in other cases will bear on the fillers 16-17 forming parts of the outer unit O, Fig. 4. The spaced channels 2-3 and the spaced fillers 16-17 provide a recess just wide enough to clear the diameter of the wire 10; thus holding the bars of the looped part 10^a in definite superposed relation.

In Fig. 9 is shown a form for a column in which the panels P are girdled by short sections or units I and O which are telescoped and pinned at 25 to a length somewhat less than the width of the panel. The ends of the units are diagonally connected across the corners by stirrups 26 which have loop ends 27 bearing against end straps 28 on the inner unit I. The other ends of the stirrups have pegs 29 to drive down back of end clips 15.

What is claimed is:

1. A concrete form stay including an inner unit comprising spaced channel members rigidly secured with backs in spaced relation and having outward turned flanges, means connecting the spaced channel backs, and an outer unit having outer members sliding on faces of the inner unit and having flanges in a com-

mon plane with flanges of the inner unit to support mold panels, and means connecting the members of the outer unit.

2. A concrete form stay including an inner unit comprising spaced channel members rigidly secured with backs in spaced relation and having out turned flanges, means connecting the spaced channel backs, and an outer unit having outer members sliding on faces of the inner unit and having flanges in a common plane with flanges of the inner unit to support mold panels, and means connecting the members of the outer unit; said means including U-clips straddling the inner unit.

3. A concrete form stay including an inner unit comprising spaced channel members rigidly secured with backs in spaced relation and having out turned flanges, means connecting the spaced channel backs, and an outer unit having outer members sliding on faces of the inner unit and having flanges in a com-

mon plane with flanges of the inner unit to support mold panels, and means connecting the members of the outer unit, and strips on the outer unit forming a bearing means for 23 tie-wire apparatus.

4. A concrete form stay including a hollow inner unit and an outer unit telescoping thereon; said units presenting registered chambers, and form tie-wires having loops extending into said chambers and interlocking on opposite, coordinate stays to hold them in position.

5. A concrete form stay including an inner unit and an outer unit telescoping therein; 35 said units presenting coaxial chambers and flush form supporting faces, means holding the units in guided, slidable relation, and means interlocking the units in telescopic adjustment.
